BEAM AND THE LIKE FOR BUILDING CONSTRUCTION

Albert Rafter, Glen Ridge, N. J., assignor to Rafter Machine Company, Belleville, N. J., a partnership composed of Albert Rafter and John C. Rafter, Jr.

Application January 20, 1934, Serial No. 707,515

6 Claims. (Cl. 72—61)

This invention relates to improvements in beams and boards and the like for use in building construction, and more particularly to such beams and boards which comprise a combination of metallic members and a cementitious material. In building construction, it has heretofore been the general practice to use steel beams and steel members because of their great strength and fire-resisting qualities. However, insofar as fire resistance is concerned, the steel beam is not as effective as is generally believed, for steel is a good conductor of heat, and in the presence of intense heat the strength of the beam or member is considerably decreased, which results, in many instances, in a complete collapse of buildings caused by buckling, bending and failure of the steel members.

It is an object of this invention to provide building construction beams and boards which have all of the strength of the well-known steel members and at the same time are protected from the effects of intense heat, by fire-resisting cementitious material.

A further object is the provision of building construction members having metallic elements, and filled or covered with a cementitious material such as gypsum or the like, so that the building member has a finished appearance and is adapted to be effectively used in numerous situations without requiring finishing as is the case with the usual steel building member.

A further object is the provision of building members formed of steel elements and a cementitious material, the steel elements being so shaped as to provide very great strength in comparison to the strength of the ordinary steel member of the same weight.

These and other advantageous objects which will later appear, are accomplished by the simple and practical construction and arrangement of parts hereinafter described and exhibited in the accompanying drawings, forming part hereof, and in which:

Fig. 1 is a sectional view of a beam constructed in accordance with my invention,

Fig. 2 is a side elevational view of a metal element used in the beam shown in Fig. 1,

Fig. 3 is a sectional view of a modified form of beam,

Fig. 4 is a side elevational view of a metal element used in the beam shown in Fig. 3,

Fig. 5 is a sectional view of another modification, and

Fig. 6 is a side elevational view of the metal element used therein,

Fig. 7 is a cross-sectional view of the metal element,

Fig. 8 is a side elevational view of the metal element used in the beam shown in Fig. 7,

Fig. 9 is a cross-sectional view of a further modified form,

Fig. 10 is a side elevational view of the metal element used in the beam shown in Fig. 9,

Fig. 11 is a cross-sectional view of a further modified form,

Fig. 12 is a side elevational view of the metal element used in the beam shown in Fig. 11,

Fig. 13 is a cross-sectional view of a further modified form, and

Fig. 14 is a side elevational view of the metal element used in the beam shown in Fig. 13.

Referring to Fig. 1, a building beam is shown to comprise a channelled metal member having side walls or flanges 15 and a bottom wall or web 16, from which are inwardly struck a plurality of spaced cylindrical flanges 17, the side walls 15 being provided with inwardly directed flanges 18, which in turn, have right-angled inwardly directed portions 19. The channel is filled with a cementitious material 20, such as gypsum or the like, which material is forced around and within the cylindrical flanges 17. It will be noted that the cylindrical flanges are arranged so that considerable metal is taken from the center line of the bottom wall 16 of the channel and disposed near the side walls 15 thereby increasing the amount of metal nearer the side walls, and considerably increasing the bending strength of the beam.

The cementitious material filling the channel enables a compact and finished beam well adapted for use in many situations in building construction, at the same time providing heat insulation to protect the metallic channel member.

In Figs. 3 and 4 is shown a modified form in which a center web plate has struck from the center line thereof a plurality of spaced central flanges 21 and 22, the flanges 21 being struck in one direction and the flanges 22 being struck in an opposite direction. The plate 20 is provided at its edges with right-angled flanges 23

to which are welded channel member 24, the side walls 25 of which are provided with inturned flanges 26. A cementitious material is packed into the cylindrical flanges and around the plate 20 and in the channels 24 as shown in Fig. 3. By

having the flanges 21 and 22 struck out in opposite directions as explained and shown, means are provided for holding the cementitious material very effectively on the web plate 20.

In Figs. 5 and 6 is shown a modified form comprising a metal channel member having a bottom wall or web 27 and side walls or flanges 28, from which are inwardly struck a plurality of spaced cylindrical flanges 29. The side walls 28 are provided with right-angular flanges 30 which are turned back upon themselves to form hooks 31 which cooperate with hooks 32 on a plate 33, which is positioned between flanges 30 as shown in Fig. 5. The channel is filled with the cementitious material, which is effectively held in position by the cylindrical flanges 29, the latter also giving great strength to the beam without increasing the weight, due to the disposing of metal 10 from the longitudinal center line of the side walls to a position near the bottom wall and the flanges 30.

In Figs. 7 and 8 is shown a further modification wherein a pair of channelled members are spaced from each other, each of said members having side walls or flanges 34 and a bottom wall or web 35 from which are struck inwardly a plurality of spaced cylindrical flanges 36. The side walls 34 are bent back upon themselves to 20 provide hooks 37 which cooperate with hooks 38 on plates 39 positioned between the side walls 34.

Figs. 9 and 10 show a further modified form in which two spaced channel members are positioned so that they open toward each other, each of said channel members having side walls or flanges 40, a bottom wall or web 41, from which are inwardly struck a plurality of cylindrical flanges 42. The side walls 40 are bent back upon 30 themselves to provide hooks 43, and a cementitious material 60 is filled in the channels, the hooks 43 and flanges 42 effectively holding the material in place. This structure provides a beam which is simple in construction, yet having great strength and fire resisting qualities.

Referring to Figs. 11 and 12 there is shown a modified form of beam in which the metal members are almost completely covered by a cementitious material. The beam comprises two spaced metal plates 44 each of which has flanges 45, which are bent back upon themselves to provide hooks 46; and struck alternately outwardly and inwardly along the longitudinal center line of each plate are a plurality of spaced cylindrical flanges 47 and 48. Cementitious material is packed into and around the flanges 47 and the hooked portions 46 and between the plates 44 as shown in Fig. 11 so that when the beam is completed the flanges 45 are the only metal parts exposed.

In Figs. 13 and 14 is shown a modified form of beam comprising two metal plates 49 of similar shape, each of said plates having struck inwardly along the longitudinal center line thereof a plurality of cylindrical flanges 50, the cylindrical flanges of the two plates abutting each other as shown in Fig. 13. Each plate is provided with flanges 51 having hooked portions 52. Cementitious material is packed all around the plates 60 and forced in the cylindrical flanges 50 and between the flanges 51 so that the only metal parts exposed when the beam is completed are the flanges 51. Such a beam has great strength and high fire-resisting characteristics.

From the above description it will be seen that I have provided a building beam of great strength and simple structure which has high fire-resisting characteristics. The metal members used in

constructing these beams are preferably formed from sheet material by passing flat sheets of metal between properly shaped die rolls. In this manner, the metal elements can be formed very rapidly and at a small cost. It is obvious that the means disclosed herein have great tensile strength; and the compressive and bending strength of the beams are considerably increased by the removing of metal from the longitudinal center lines of the metal elements, to a position 10 adjacent the edges of the metal elements, it being well known that the metal along the longitudinal center line is not affected one way or the other as far as bending is concerned.

The foregoing disclosure is to be regarded as 15 descriptive and illustrative only, and not as restrictive or limitative of the invention, of which obviously an embodiment may be constructed including many modifications, without departing from the general scope herein indicated and de- 20 noted in the appended claims.

Having thus described my invention what I claim as new and desire to secure by Letters Patent, is:

1. In a beam for building construction, a metal 25 channel member having a web and side flanges, said web having a plurality of spaced cylindrical flanges struck alternately inwardly and outwardly along the longitudinal center line thereof.

2. In a beam for building construction, a web 30 plate having right angularly directed flanges and a plurality of spaced cylindrical flanges struck alternately inwardly and outwardly therefrom along the longitudinal center line thereof, plates attached to the right angularly directed flanges 35 and cementitious material packed between said plates and completely covering the web plate.

3. In a beam for building construction, a pair 40 of spaced plates, each of said plates having right angular directed flanges, and a plurality of spaced cylindrical flanges struck therefrom along the longitudinal center line thereof, the cylindrical flanges of the two plates abutting each other, and cementitious material packed through said cylindrical flanges and around said plates so that 45 the right angular directed flanges are the only part of the plates exposed.

4. In a beam for building construction, a pair 50 of spaced plates, each of said plates having right angular flanges, and a plurality of spaced cylindrical flanges struck outwardly along the longitudinal center line thereof, and cementitious material packed around said plates and through the cylindrical flanges so that said right angular flanges are the only portions of the plates exposed. 55

5. A beam for building construction, comprising a channel member having a web and right angular directed flanges provided with inturned flanges, said web having a plurality of spaced portions struck inwardly along the longitudinal center line thereof to form tubular flanges, and cementitious material packed in said channel member between the web and said flanges and around said spaced portions. 60

6. In a beam for building construction, a metal 65 channel member having a web and side flanges, said web having a plurality of spaced portions struck alternately inwardly and outwardly along the longitudinal center line thereof, and cementitious material packed in said channel member 70 between said web and flanges and around said spaced portions.

ALBERT Rafter.
